UNITED STATES PATENT OFFICE.

EMANUEL PISKO, OF NEW YORK, N. Y., ASSIGNOR OF FIVE-EIGHTHS TO
JOSEPH SEIDENBERG AND FRANCIS A. SCHLEIFF, JR., OF SAME PLACE.

CIGAR-BUNCHING MACHINE.

SPECIFICATION forming part of Letters Patent No. 508,293, dated August 15, 1893.

Application filed July 7, 1893. Serial No. 479,853. (No model.)

To all whom it may concern:

Be it known that I, EMANUEL PISKO, a citizen of the United States, residing in the city, county, and State of New York, have invented 5 certain new and useful Improvements in Cigar-Bunching Machines, of which the following is a specification.

In the bunch-making machines heretofore in use, the tobacco was fed between rollers 10 and supplied in compressed state to a bunch-forming head which was provided with a cutter that severed a quantity of tobacco sufficient for a filler and dropped the same onto a rolling apron where the cut-off charge of 15 tobacco was rolled into a binder. The cutting off of the filler by a cutter-knife from the compressed tobacco fed to the bunching head is objectionable on many grounds, mainly however because the quantity cut off 20 in this manner is not a satisfactory substitute for a filler made by hand and does not produce cigars of the required degree of perfection.

As the main object of bunching machines 25 is to imitate as closely as possible the manipulations to which the tobacco is subjected when forming the filler by hand, it is obvious that the better this is accomplished, the more general will be their introduction.

30 The object of this invention is to construct a cigar-bunching machine in which the quantity of tobacco necessary for a filler is not cut off by a cutting knife, but gripped and pulled away from the remaining quantity of 35 tobacco and then dropped on or conducted to a suitable rolling mechanism, so that the tearing or splitting of the leaves by hand in forming long-filler bunches is closely imitated and a bunch produced that has nearly if not 40 entirely the characteristics of a hand-made bunch.

For this purpose my invention consists of 45 a cigar-bunching machine, which comprises endless feed-belts between which the tobacco is fed forward, a vertically reciprocating retaining device for the tobacco, an oscillating cup provided with an independently swinging jaw by which the tobacco fed forward by the belts is gripped and torn away from the 50 retaining device and then dropped by the oscillating motion and release of the grip-

ping jaw onto the apron of the rolling mechanism, as will be fully described hereinafter and finally pointed out in the claims.

In the accompanying drawings, which form 55 a part of the specification, Figure 1, represents a front-elevation of my improved cigar-bunching machine, parts of said figure being shown as broken off so as to show some of the operated parts behind the same. Fig. 2, is a 60 vertical longitudinal section on line 2 2, Fig. 1. Fig. 2^a, is a detail front-view of the mechanism for intermittent motion to the feed-belts. Fig. 3, is a side-elevation of the machine, with a part of the frame broken off, to 65 show portions of the actuating mechanism back of the same. Fig. 3^a is a detail-section of the mechanism for moving the feed-belts. Fig. 4 is a plan-view of the machine, partly in horizontal section, on line 4 4, Fig. 2. Figs. 70 5, 6 and 7 are vertical transverse sections, drawn on a larger scale and showing the tobacco-separating parts of my improved machine in their successive positions of receiving, separating and dropping the quantity 75 necessary for a filler; and Figs. 8 and 9 are detail sections of the rolling device, showing the same in the act of rolling the filler into a binder, and of delivering the bunch.

Similar letters of reference indicate corresponding parts.

Referring to the drawings, A represents the supporting-frame of my improved cigar-bunching machine, which frame consists of two upright standards A' that are connected 85 by transverse braces and tie-rods a', as appears clearly from Figs. 1 and 4. On the supporting-frame A is arranged a stationary table B over which is conducted the lower endless feed-apron B' which is mounted on guiding and stretching rollers b b', that are arranged respectively at opposite ends of the stationary table B. The stretching roller b' is provided with adjusting screws for the bearings of said roller, so that the proper degree 95 of tension can be imparted to the endless feed-apron B'. At each side of the endless feed-apron B' is arranged a rail B² which projects above the level of the feed-apron B' and which is capable of lateral adjustment by 100 means of transverse bolts b² passing through lateral slots b³ of the rail B² and clamp screws

b⁴, so that the rail can be adjusted near to or away from the endless apron *B'* for the purpose of providing the required space for the tobacco required for different lengths of fillers. The tobacco to be worked up into fillers is spread over the feed-apron *B'* by the attendant between the raised rails *B²* and fed forward intermittently by the apron in the direction of the arrow, shown in Figs. 2 and 4. The means by which this intermittent motion is imparted to the feed-apron *B'* will be fully described hereinafter.

Above the lower apron *B'* and parallel thereto or nearly so, is arranged a second endless apron *C*, which is supported by a driving-roller *d* at one end and an adjustable stretching-roller *d'* at the other end. The feed-apron *C* is made of less length than the lower feed-apron *B'*, and serves to compress the tobacco that is spread over the lower feed-apron *B'* so as to feed the same with the apron *B'* in forward direction toward the mechanism by which the filler is formed. The guide-roller *d* of the upper feed-apron *C* is guided in fixed standards *d²* of the supporting-frame, while the standards *d³* in which the stretching-roller *d'* is journaled, rests loosely on the side-rails *B²*. Intermittent motion is imparted to the upper feed-apron *C* by the driving-roller *d* which is provided with radial pins at each end, said pins engaging eyelets arranged in the edges of the feed-apron *C* so as to produce thereby a positive forward motion without relying merely on the friction between the feed-apron and its driving and stretching rollers. The same positive feed-motion may be imparted to the lower feed-apron *B'* by providing the driving-roller *b* with pins, which pins engage eyelets in the edges of the belt *B'*. Below the lower feed-apron *B'* and somewhat in front of the same, is arranged a bunch-rolling device *E*, which may be made of any approved construction, that shown in the drawings consisting of a horizontally-reciprocating rolling-table *e*, to the front end of which one end of the rolling-apron *e'* is attached. The opposite end of the bunching-apron *e'* is attached to a transverse bar *e²* of the supporting-frame *A* while the bunching-roller *e³* is arranged below the apron and mounted in the U-shaped front portion of an intermittently-reciprocating slide-frame *E'* which extends over both sides of the rolling-table and is guided by means of side-rails *e⁴* in fixed ways *e⁵* which are supported in brackets *e⁶* that are attached to the front standards *A'* of the supporting-frame *A*, as shown clearly in Fig. 1. The under side of the rolling-table *e* is connected by a pivot-link *e^x* with an oscillating elbow-lever *e⁷* which is pivoted to the frame *A* and provided with an anti-friction roller at its apex, said roller extending into the cam-groove of a cam *e⁸*, which is placed on a shaft *S'*. The shaft *S'* is supported in bearings at the lower part of the main-frame *A*. The cam-groove of the cam *e⁸* is made in such a shape that the proper forward and backward motion is imparted to

the rolling-table *e*. The same cam is provided at its circumference with two lugs *e⁹* and *e¹⁰* which are provided with pins, the pin on the lug *e⁹* engaging a downwardly-extending rear arm *e¹¹* of the slide-frame *E'* so as to impart forward motion to the same, and the bunching-roller, while the pin on the lug *e¹⁰* engages a fulcrumed lever *e¹²* that is connected by a chain *e¹³* that passes over a guide-roller *e¹⁴* with a hook *e¹⁵* at the rear part of the slide-frame *E'*; so that by the engagement of the pin on the lug *e¹⁰* with the end of the lever *e¹²* a motion in an opposite direction is imparted to the slide-frame *E'* and the bunching-roller *e³*. The pin on the lug *e⁹* extends in opposite direction to the pin on the lug *e¹⁰* one pin being placed in the path of the downwardly-extending arm *e¹¹* of the slide-frame *E'*, while the other pin is placed in the path of the upper end of the return-lever *e¹²*. The slide-frame *E'* receives a forward motion with the bunching-roller *e³* mounted on the same and produces the rolling of the filler into the binder which is placed on that portion of the bunching-apron which is over the rolling-table *e*. At the front end of the rolling-table *e* is arranged, a spring-finger *e¹⁶* to which the bunch is delivered after it is rolled by the joint action of the rolling-apron *e'* and bunching-roller *e³* supported on the sliding frame *E'* the bunch being rolled in the pocket or bight of the rolling-apron formed in front of the bunching-roller in the usual well known manner in cigar-bunching machines.

I do not confine myself to the special construction of rolling mechanism, shown in the drawings, as any other approved mechanism can be used for this purpose.

Adjacent to and on a level with the front-end of the lower feed-apron *B'* and vertically below the front-end of the other feed-apron *C* is arranged a transverse horizontal table or bridge *F* onto which the tobacco is fed by the feed-aprons *B'* and *C*, it being then retained on said table by the serrated lower edge of a vertically reciprocating gate *G*, that is guided in upright ways *g* of the supporting frame *A*, said gate being provided with a projection or toe *g'* at its upper part which is acted upon by a cam *g²* that presses the gate in downward direction and holds thereby the tobacco on the table *F*, until the cam *g²* releases the toe *g'*. As soon as the cam has passed the toe *g'*, the gate *G* is raised again in its guide-ways by the action of a yoke-shaped oscillating lever *g⁴* which is pivoted at its lower end to a transverse shaft *g⁵* supported in bearings of the supporting frame. The upper end of the lever *g⁴* is connected by a chain *g⁶* that passes over a guide-roller *g⁷* with a hook or eye *g⁸* at the upper end of the gate *G*. Cams *g⁹* located one on each side of the cam *g²* act on the oscillating lever *g⁴* and move the same in backward direction, so as to produce thereby the lifting of the gate *G* to a sufficient height so that the tobacco can be fed below its lower serrated edge in forward direction over the

stationary table or bridge F. In front of the stationary table or bridge F is arranged a receiving-cup H which is pivoted by a transverse pivot-shaft h^x to fixed standards h^0 of the supporting frame, so as to be readily tilted on said shaft. The lower front-edge of the receiving cup H is in its normal position on a level with the upper surface of the stationary table or bridge F, as shown clearly in Figs. 2 and 5. At some distance from its edge the receiving cup H is provided with a transverse lip h and above the same with a gripping jaw H', which is pivoted to the side walls of the receiving cup H and which is acted upon by a flat spring h' attached to the rear-part of the receiving cup H. During the forward motion of the tobacco, produced by the feed-belts B' and C, the gate G is in raised position and the gripping jaw H' of the receiving-cup H is in open position on a level or nearly so with the lower serrated edge of the gate G, as shown in Figs. 2 and 5. A quantity of tobacco, sufficient to form a filler, is moved forward by the feed-belt until it abuts against the fixed lip h in the receiving-cup H. The gate G is then moved in downward direction so as to press firmly on the tobacco on the table or bridge F. At the same time, the gripping-jaw H' is pressed in downward direction by a vertically-reciprocating slide-piece H², the lower end of which engages the front-end of the gripping-jaw at the proper time. The slide-piece H² is guided by slots on suitable guide-studs h^3 of the supporting frame, as shown in Figs. 5, 6 and 7, and is moved in downward direction by a cam h^3 , which engages a projecting lug h^4 attached to the slide-piece H². By the downward motion of the slide-piece H² the gripping-jaw H' is lowered and pressed toward the edge of the receiving cup H so as to firmly compress the tobacco fed into the cup and hold the same between the edges of the gripping-jaw H' and cup H. A tilting motion is next imparted to the receiving cup H by the pressure of the slide-piece H² on the gripping-jaw H', the downward motion of the slide-piece H² being continued by the cam h^3 , so that the tobacco confined in the cup is separated or torn off from the main-portion of the tobacco which is firmly held between the table or bridge F and the gate G, as shown in Fig. 6. The receiving cup H is connected by a pivot-pin h^5 at one side with a vertically-reciprocating slide-piece H³ which is connected at its upper end with a curved lever-arm h^6 that is also pivoted to the transverse shaft g^5 . The curved lever-arm h^6 is acted upon by a cam h^7 on the upper cam-shaft of the machine, said cam being provided with an eccentric portion and a shoulder at the end of the eccentric portion, as shown in Fig. 2. At the moment when the lever-arm h^6 leaves the eccentric portion of the cam h^7 and drops on the concentric portion of the same, the connecting-rod H³ is moved in downward direction and imparts a quick tilting motion to the receiving cup H, as shown in Fig. 7. This tilting motion moves the cup away from the gripping-jaw H' and permits the dropping of the entire quantity of tobacco which was separated or torn off by the joint action of the receiving-cup and gripping-jaw H' into the pocket or bight formed in the loose rolling apron e', as shown in Fig. 7. As soon as the tobacco which forms the filler is deposited, it is rolled into the binder placed on the apron and the bunch obtained is taken up to the spring-holder at the front-end of the rolling mechanism. The receiving-cup H is held in tilted position until the eccentric portion of the cam h^7 gradually raises the curved lever-arm h^6 and returns thereby the receiving-cup H into its initial position, with its receiving edge on a level with the stationary table. The next operation of feeding the tobacco, retaining the same on the table F by the gate G, compressing the projecting portion between the adjacent edge of the receiving cup and the gripping-jaw and the tearing off of the projecting portion by the oscillating motion imparted to the gripping-jaw and cup and the dropping of the tobacco separated or torn off, is again repeated and thus one bunch after the other formed in regular manner, one at each revolution of the driving shaft.

The operative parts of my machine receive motion from a driving shaft S which is arranged in suitable bearings of the lower part of the supporting-frame A. To one end of the driving shaft S is applied a fast and loose pulley in the usual manner on either one of which the belt is shifted in starting or stopping the machine. On the shaft S is arranged a pinion p which meshes with a gear-wheel w that is placed on the intermediate shaft S', which turns also in bearings of the lower part of the supporting frame A. To the intermediate shaft S' is keyed the cam e⁸ by which reciprocating motion is imparted to the rolling table e and to the slide-frame E' of the bunching roller e⁸. To the outer end of the shaft S' is attached a motion-transmitting gear-wheel w' of smaller diameter than the large gear-wheel w, the smaller gear-wheel w' meshing with an intermediate gear-wheel w², which turns a short shaft w³ on one of the standards of the frame A, the intermediate gear-wheel w² meshing with a third gear-wheel w⁴, that is attached to the cam-shaft S² which is supported in bearings at the upper part of the supporting frame A and on which are arranged the different cams by which motion is imparted to the reciprocating gate G, the receiving cup H and the gripping-jaw H', as before described. A clutch p' is arranged near the pinion p on the driving shaft S, said clutch p' being engaged by the rear-end of a fulcrumed lever L, the front-end of which is curved sidewise, so as to be within easy reach of the attendant, who is thereby readily enabled to start or stop the machine, by simply shifting the

clutch-lever L and throwing thereby the pinion p in or out of gear with the clutch-mechanism of the driving-shaft S.

The intermittent motion of the feed-belts B' and C is produced by a cam i on the upper shaft S², which cam engages the antifriction-roller of a fulcrumed elbow-lever i' that is placed loosely on a transverse shaft i^2 of the supporting frame, as shown in Figs. 2^a and 3^a. The lower arm of the elbow-lever i' is connected by a link i^3 with an oscillating arm i^4 that is loosely placed on the shaft of the driving roller d of the upper feed-belt C, as shown in Figs. 2^a and 3^a. To the hub of the loose arm i^4 is applied a chain i^5 the lower end of which is connected to the hook-shaped end of a flat spring i^6 which is attached to the supporting frame A. On the shaft of the driving roller d are arranged sidewise of each other two ratchet-wheels i^7 which are engaged by two pawls i^8 , pivoted to an oscillating keeper i^9 on the lever-arm i^4 . The cam i imparts oscillating motion to the elbow-lever i' and to the elbow-arm i^4 and the keeper i^9 and transmits thereby by the pawls i^8 and the ratchet-wheels i^7 intermittent rotary motion to a pinion i^{10} on the shaft of the feed-roller d and thereby an intermittent forward motion to the upper feed-belt C. The pinion i^{10} meshes with the pinion i^{11} on the shaft of the lower feed-roller b and imparts thereby intermittent motion to the lower feed-belt B', said motion being sufficient to feed forward the quantity of tobacco required for a filler. After the cam i has passed the antifriction roller of the elbow-lever i' , the oscillating arm i^4 with the keeper i^9 is returned by the spring i^6 to its former position so that the pawls are moved over the teeth of the ratchet-wheels and without engaging the same, while the belts are retained in position ready for the next forward motion of the feed-belts, when the cam i engages at the next rotation on the shaft S² the elbow lever i' and transmits by the intermediate pawl and ratchet mechanism described intermittent forward motion to the feed-belts. For regulating the degree of forward motion of the feed-belts, a screw-spindle k is arranged which passes through one of the upright standards A' of the supporting-frame A and is provided with a wheel k' at its outer end, that is set along a graduated gage k^2 attached to the supporting frame A, as shown clearly in Fig. 4. The inner end of the screw-spindle k is provided with a conically-shaped stop-piece k^3 that extends into the path of the upper arm of the elbow lever i' and serves to arrest the motion of the latter in one direction, while the cam i imparts oscillating motion to the upper arm of the elbow-lever i' in the other direction. The more the stop cone k^3 is adjusted in inward direction the smaller will be the throw of the elbow-lever i' and the smaller will be the feed-motion of the feed-belts, while the more the stop cone k^3 is moved away from the elbow-lever i' the greater will be the throw of the

elbow-lever i' and the greater the feed-motion of the feed-belts, for the reason that the smaller end of the stop-cone is placed in the path of the upper arm of the oscillating elbow-lever i' , whereby a greater oscillating motion is imparted to the same by the action of the cam i and the spring i^6 . In this manner the motion of the feed-belts may be exactly regulated according to the quantity of tobacco desired for the filler and bunch to be produced.

The operation of my improved cigar-bunching machine is as follows: The tobacco from which the fillers are to be made, is spread over the lower feed-belt in such a manner that the required thickness of the filler is obtained. The machine is then started and the tobacco fed successively to the working parts of the machine, care being taken that successively new quantities of tobacco are spread on the lower feed-belt, so that the continuous operation of the machine can be kept up. As the tobacco is passed under the feed-belt, it is fed forward by the slight compression imparted by the belts onto the fixed table or bridge F on which the tobacco is firmly pressed by the serrated lower edge of the descending gate G, a quantity sufficient for a filler projecting in front of the same into the receiving cup H. This projecting portion is taken hold of by the gripping-jaw H' and cup H and torn off in imitation to the motion of the hands in separating and tearing off tobacco for a long filler, it being then tilted with the cup H, dropped onto the rolling mechanism, where it is rolled with the binder into a bunch in the usual well-known manner and then placed into the mold. The position of the cams on the driving shafts of the machine is so arranged that all the different motions are produced at the proper time and that at each rotation of the driving shaft a bunch is produced.

The advantages of my cigar-bunching machine are, that a bunch is obtained which resembles much closer a hand-made bunch, than a bunch in which the filler is cut off by a cutting knife, so that cigars are finally obtained which resemble in a high degree hand-made cigars, inasmuch as the fillers contained in the same are more like hand-made fillers.

Having thus described my invention, I claim as new and desire to secure by Letters Patent—

1. The combination, with intermittently actuated feed-belts, of a stationary table or bridge in front of and on a level with the lower feed belt, a vertically reciprocating gate having a serrated lower edge above the stationary table and an intermittently oscillating receiving cup located in front of the table and provided with a pivoted and spring-actuated gripping-jaw, substantially as set forth.

2. The combination, of intermittently actuated feed-belts arranged one above the other, of a stationary table in front of and on a level with the lower feed-belt, a vertically-reciprocating gate above the said table, said gate

- having a serrated lower edge, a receiving cup arranged in front of said table, a spring-actuated gripping-jaw pivoted to the receiving-cup, means for pressing said gripping-jaw on the tobacco projecting beyond the gate, and means for tilting the cup after the gripping-jaw is moved in downward direction, so as to separate or tear off a quantity of tobacco necessary for a filler, substantially as set forth.
- 10 3. The combination, with intermittently-actuated feed - belts, a stationary table or bridge in front of and on a level with the lower feed-belt, a vertically-guided gate having a serrated lower edge, means for imparting reciprocating motion to said gate, a receiving-cup pivoted in front of the stationary table or bridge and provided with a fixed lip or abutment at some distance from its edge, a spring-actuated gripping-jaw pivoted to the receiving cup above said lip, and a rolling mechanism arranged below the receiving cup for delivering thereon the tobacco torn off by the joint action of the gripping jaw and cup, substantially as set forth.
- 15 4. The combination, of intermittently-actuated feed-belts, a stationary table or bridge in front of the lower feed-belt, a vertically-guided gate having a serrated lower edge, means for imparting reciprocating motion to said gate, a pivoted receiving cup in front of the stationary table provided with a lip or abutment at some distance from its edge, a spring-actuated gripping-jaw pivoted to the receiving-cup, means for lowering the gripping jaw and pressing the same on the tobacco projecting beyond the gate and table, means for tilting the receiving cup so as to separate or tear off the projecting quantity of tobacco and a rolling mechanism below the tilting cup so as to form a bunch after the quantity of tobacco necessary for a filler is dropped into the pocket or bight of the apron of said rolling mechanism, substantially as set forth.
- 20 5. The combination, with intermittently-actuated feed - belts, a stationary table or bridge in front of and on a level with the lower feed-belt, a vertically-guided gate having a serrated lower edge, means for imparting reciprocating motion to said gate, a receiving-cup pivoted in front of the stationary table or bridge and provided with a fixed lip or abutment at some distance from its edge, a spring-actuated gripping-jaw pivoted to the receiving cup above said lip, and a rolling mechanism arranged below the receiving cup for delivering thereon the tobacco torn off by the joint action of the gripping jaw and cup, substantially as set forth.
- 25 6. The combination, of intermittently-actuated feed-belts, a stationary table or bridge in front of the lower feed-belt, a vertically-guided gate having a serrated lower edge, means for imparting reciprocating motion to said gate, a pivoted receiving cup in front of the stationary table provided with a lip or abutment at some distance from its edge, a spring-actuated gripping-jaw pivoted to the receiving-cup, means for lowering the gripping jaw and pressing the same on the tobacco projecting beyond the gate and table, means for tilting the receiving cup so as to separate or tear off the projecting quantity of tobacco and a rolling mechanism below the tilting cup so as to form a bunch after the quantity of tobacco necessary for a filler is dropped into the pocket or bight of the apron of said rolling mechanism, substantially as set forth.

In testimony that I claim the foregoing as my invention I have signed my name in presence of two subscribing witnesses.

EMANUEL PISKO.
